(57) **CLAIM**

The ornamental design for an electric arc lighter as shown and described.

DESCRIPTION

FIG. 1 is a front view of an electric arc lighter, according to the claimed design;

FIG. 2 is a rear view of the electric arc lighter of FIG. 1; FIG. 3 is a left-side view of the electric arc lighter of FIG. 1;

FIG. 4 is a right-side view of the electric arc lighter of FIG. 1;

FIG. 5 is a top view of the electric arc lighter of FIG. 1; FIG. 6 is an enlarged top view of the electric arc lighter of FIG. 1;

FIG. 7 is a bottom view of the electric arc lighter of FIG. 1; FIG. 8 is an enlarged bottom view of the electric arc lighter of FIG. 1;

FIG. 9 is a perspective view of the electric arc lighter of FIG. 1; and,

FIG. 10 is an enlarged view of the electric arc lighter as depicted in FIG. 9.

The dot-dash broken lines surrounding details shown in FIGS. 9 and 10 are for purposes of annotating the enlarged view only and form no part of the claimed design. The evenly spaced broken lines in the drawings depict portions of the electric arc lighter that form no part of the claimed design.

1 Claim, 10 Drawing Sheets
